UNITED STATES PATENT OFFICE

ROBERT G. REDMANN, OF BRISTOL, CONNECTICUT, ASSIGNOR TO THE SESSIONS FOUNDRY COMPANY, OF BRISTOL, CONNECTICUT, A CORPORATION

INGOT MOLD

Application filed September 1, 1928. Serial No. 303,592.

My invention relates to improvements in ingot molds, of the form that is made of cast iron for use in casting ingots of non-ferrous metals, and particularly of the form that is 5 made-up of a pair of hingedly connected parts that compose the mold proper and is surmounted by a pouring cup that is mounted for swinging up and down relatively to the pouring position and that is particularly adapted 10 for use in producing ingots in the form of slabs or bars of rectangular or any desired form of cross-section, and the object of my improvement is to incorporate in such an ingot mold keeper means for cooperating with 15 the latch members at the sides of said hingedly connected parts in the form integral lugs that have relatively elongated contacting holding faces, thereby ensuring relatively long life for the parts, and also to provide improved means 20 for mounting said pouring cup that permits readily removing the cup from the mold structure for the purpose of replacement or the like.

In the accompanying drawing:—

25 Figure 1 is a front elevation of an ingot mold that is equipped with latching devices and a pouring cup in accordance with my invention.

Figure 2 is a side elevation of the same, an 30 alternative position of the cup being indicated by means of broken lines.

Figure 3 is a fragmentary front elevation of the upper portion and with part of the front mold part broken away.

35 Figure 4 is a fragmentary side elevation in part broken away to show one of the cup hinge slots covered by the movable ingot part.

Figure 5 shows the cup member by itself.

40 Figure 6 shows the details of the keeper lug and the latch arm that engages therewith.

My improved ingot mold corresponds in the general features and in the functions of the parts under conditions of use to molds that 45 are in common use. Thus the mold proper is composed of a rear fixed part 10 and a front part 11 that cooperate to provide a mold cavity 12 that in the present instance is of rectangular form of cross-section. Said 50 parts 10 and 11 are hingedly connected by

means of suitable lugs at their lower ends and a pintle-bar 13.

At the upper end is a pouring cup 14 that is mounted for swinging back and forth and that in the forward position is in registration by its delivery openings 15 with the mold cavity 12. 55

At the sides of the mold parts 10 and 11 are provided latch means in the form of a latching-bar 16 and a keeper 17 for cooperating 60 therewith.

My improvements pertain to the specific form of the keeper 17 that is provided and to the means for the pivotal mounting of the cup 14. 65

The latching-bar 16 in each case is pivotally connected to by its rear end 18 to the rear fixed part 10 by means of a pintle bar 19 so as to swing downwardly across the side faces of the parts 10 and 11. At the front end 70 portion of the bar 16 is an engaging nose 20 that has a contacting face 21 of relatively elongated form.

I find it desirable to utilize under holding conditions substantially the whole or the 75 major part of said contacting face 21. I effect this result by providing the keeper lug 17 with a cooperating contacting face 22 that is substantially the counter-part of the face 21.

Also, as an important detail, the keeper lugs 17 are cast integral with the front mold part 11. 80

Also, the keeper lugs 17 are properly shaped in the casting, so that no machining 85 thereof is done in adapting them for the purpose described.

The latch bars 16 are drop-forged parts and the machining thereof is confined to the rear end 18 for the pivotal connection. 90

The steel of the bar and the cast iron of the lug, as diverse materials, cooperate to assist in providing the holding friction under locking conditions.

The cast keeper lugs 17 replace a bar of 95 steel, which has been used heretofore.

A bar has likewise been used for the hinge connection for the pouring cup.

In lieu thereof I provide integral pivotal lugs 23 at the lower end of the cup structure 100

that engage in recesses 24 that are provided in the side wall structure 25 of the rear fixed part 10.

The cup 14 has side bars 26 that project downwardly in extension of the side walls and that by their lower ends overhang the opposed and adjacent upper end portions of the mold parts 10 and 11 and more specifically are closely adjacent the upper end portion 27 of the rear fixed part 10. The pivot receiving recesses 24 are provided in said upper end portion 27 and the pivotal lugs 23 project laterally inwardly from the side bars 26 so as to be housed therein.

15 The recesses 24 are open inwardly towards the mold cavity 12 and under operating conditions these are closed by the opposed and adjacent portions 28 of the front moving mold part 11. Thus the cup can be freely removed 20 at any time while the mold is open.

The advantages of the improved constructions shown and described are emphasized by the fact that ingot molds of the form described are used in groups, arranged in a row or 25 mounted on a turn-table for the pouring, and any weakness that throws a mold out of commission operates to interrupt operations.

The latching of the mold parts must be tight. In the construction described, the lugs 30 outwear that latch bars.

As to the cups, these burn out. The construction described permits of replacement in situ and without any machining operation or tool-work whatsoever.

35 I claim as my invention:—

1. In an ingot mold having hingedly connected mold parts that are surmounted by a pouring cup, latch mechanism comprising a latch bar pivotally connected by one end to 40 one of said parts and having an engaging nose at the other end, a lug on the other of said parts for serving as a keeper in cooperation with said nose, and said nose and lug having each a relatively elongated contacting face for cooperating with the face of the other under locking conditions.

2. In an ingot mold comprising a mold proper and a cup surmounting the same, said mold being composed of two hingedly connected parts that meet in face-to-face contact, said cup having downwardly projecting supporting bars, pintle lugs extending inwardly laterally from said bars, one of said mold parts having recesses that open from 50 its meeting face and having walls for generally enclosing said lugs, and the face of the other of said mold parts serving as a closure for said recesses.

60 3. In latch construction for holding together the two parts of an ingot mold, a latch bar pivoted to one of said parts and having a hook-like engaging nose and a lug on the other of said parts having a contact face for cooperating with said nose, and said 65 nose and contact face being shaped to provide

opposed and contacting holding faces that are relatively extended in the direction of the angular movement of the latch bar on its pivot.

4. In pouring cup construction for ingot molds, the two mold parts meeting by their edges in face to face contact, a pouring cup surmounting said parts and provided with supporting arms that extend downwardly alongside said edges, short pintles on the 70 ends of said arms for providing operative connection of the cup with said parts projecting inwardly and in alignment one with the other, and the structure of at least one of said parts being provided with recesses 75 that serve as receiving sockets for said pintles for effecting such operative connection.
